[57] CLAIM

The ornamental design for a table, as shown and described.

DESCRIPTION

FIG. 1 is a perspective view of a table showing my design;

FIG. 2 is a side view of the table shown in FIG. 1;

FIG. 3 is a plan view of the table shown in FIG. 1;

FIG. 4 is a perspective view of a table showing a modified form of my new design;

FIG. 5 is a side view of the table shown in FIG. 4; and

FIG. 6 is a plan view of the table shown in FIG. 4. The bottom of each embodiment is unornamented, and the views of the side of each embodiment opposite those shown in FIGS. 2 and 5 are identical to the side views shown in FIGS. 2 and 5, respectively.

FIG. 1.

FIG. 2.

FIG. 3.

FIG. 4.

FIG. 5.

FIG. 6.
